UNITED STATES PATENT OFFICE.

HENRICH WASILIEWITSCH WAGENER, OF MOSCOW, RUSSIA.

OIL-HEATER.

No. 796,949.

Specification of Letters Patent.

Patented Aug. 8, 1905.

Application filed April 23, 1903. Serial No. 154,030.

To all whom it may concern:

Be it known that I, HENRICH WASILIEWITSCH WAGENER, a subject of the Emperor of Russia, residing at Moscow, Russia, have invented certain new and useful Improvements in Oil-Heaters, of which the following is a specification.

The present invention relates to an apparatus for oil-heating.

In the accompanying drawings, which illustrate the invention, Figure 1 is a front elevation of the apparatus; Fig. 2, a longitudinal vertical section thereof on the line A B, Fig. 1; and Fig. 3 is a horizontal section of the apparatus on lines C D, Fig. 1.

The apparatus consists of a water-supply pipe *a* and a supply-pipe *b* for naphtha, which is led to a spraying-nozzle *c*. The firing is shut off by a plate *d*, in which is set a fire-door *e*, with ventilating hit-and-miss arrangement *f*. The ventilating hit-and-miss arrangement has in its center an opening *g* and on one side a reflector *h*. Within the plate *d* is further furnished a small door *i* for igniting. At the side there is secured to the plate *d* a steam-collector *k* by means of brackets. This is provided below with a draining-cock *l* and at the top with a safety-valve *m*, which opens when the pressure becomes too great. The steam is generated in a coil-pipe *n*, supplied by the water-pipe *a*, and the steam passes from the coil-pipe into the steam-collector. The coil-pipe is protected against too great heat by a plate *s*. Below this is provided a pan *t*, which is used for igniting. The steam passes from the collector through a pipe governed by valve *o* toward the swivel-joint *p* and through the pipe *r* into the nozzle *c*. The oil to be burned comes from the pipe *b* and is also led through the swivel-joint *p*, but separated from the steam, and through the pipe *r'* to the nozzle, where it is atomized by the steam, so that its combustion is complete.

The nozzle, together with the two pipes *r* and *r'*, can be turned in the swivel-joint *p*.

To start the apparatus working, some oil is placed in the pan *t* and lighted with wood-shavings or a piece of paper, when water has been admitted into the coil-pipe *n*. After little time steam will be evolved and will fill the steam-collector *k*. The water condensing within the steam-collector is let out by the cock *l*, and as soon as dry steam is procured the valve *o* is opened and the valve of the atomizer *c*. Finally, the oil-inlet valve in the pipe *b* is opened, and by means of this valve and the ventilator *f* the entry of the fuel and air is regulated. The fuel lights at the flame burning in the pan *t*, and the result is a smokeless dazzling white flame, which keeps up the generation of steam in the coil-pipe *n*.

What I claim, and desire to secure by Letters Patent of the United States, is—

In a furnace the combination of the fire-chamber, a steam-generator therein, a steam-collector communicating with the generator and located outside the chamber, a fuel-inlet, a conical deflector within the chamber around said fuel-inlet, air-inlets around the fuel-inlet; with an oil-pipe and a steam-pipe rotatably mounted upon a common support, an atomizing-nozzle connected to the free ends of said pipes and adapted to be introduced into said fuel-inlet, a valved oil-supply pipe communicating with the oil feed-pipe through said support, and a valved steam-supply pipe connected with said collector and communicating with said steam-feed pipe through said support, all substantially as and for the purpose described.

In testimony whereof I have hereunto set my hand in the presence of two witnesses.

HENRICH WASILIEWITSCH WAGENER.
